METHOD OF ANCHORING LATCH BOLT CASINGS

Fred J. Russell, 3800 Don Felipe Drive,
Los Angeles, Calif.

Filed July 31, 1961, Ser. No. 128,088
2 Claims. (Cl. 29—453)

The invention relates to locks and latches and has particular reference to latch bolts frequently identified as tubular type latch assemblies wherein there is provided a housing for the latch bolt mechanism separate and apart from the remaining portion of the lock which is interconnected with the lock upon installation of the several parts in a door.

This is a continuation-in-part of copending applications Serial No. 707,931, filed January 9, 1958 (now abandoned) and Serial No. 779,134, filed December 9, 1958, now Patent 3,026,137, issued March 20, 1962.

One of the problems which regularly confronts installers of typical cylinder lock sets is the necessity for having to provide a non-circular latch face and for having to attach the latch face to the door edge with wood screws.

It is accordingly among the objects of the invention to permit mortising for the face of the latch bolt casing by use of a step drill.

Another object of the invention is to provide a new and improved method for anchoring a latch bolt casing which resiliently braces between the latch bolt casing and the edge of the side hole in the door itself, thereby fastening the latch bolt casing to the door in a firm and dependable fashion in advance of mounting the operating mechanism in place.

Still another object of the invention is to provide a new and improved method for anchoring a latch bolt casing which mounts the latch bolt casing independently in the door quickly and easily without need to secure the latch bolt casing face to the door edge by means of wood screws or other means.

Still another object of the invention is to provide a new and improved method of anchoring latch bolt casings which is sufficiently simple in its operation to permit acceptable installations to be made without special skill being involved.

Still further among the objects of the invention is to provide a new and improved latch bolt casing anchor method which is sufficient to compensate for variations in side hole locations in the door.

With these and other objects in view, the invention consists in the method of operation and the construction, arrangement and combination of the various parts of the device whereby the objects contemplated are attained, as hereinafter set forth, pointed out in the appended claims and illustrated in the accompanying drawings.

In the drawings:

FIGURE 1 is a side elevational view of a latch bolt casing anchored in place by use of one form of the invention in a typical door and which employs the method hereinafter described.

FIGURE 2 is a horizontal sectional view taken on the line 2—2 of FIGURE 1.

FIGURE 3 is a cross-sectional view taken on the line 3—3 of FIGURE 1.

2

FIGURE 4 is a perspective view of an anchoring element of the type used in FIGURE 1, 2, and 3.

FIGURE 5 is a side elevational view of a latch bolt casing anchored in a door by use of a second form of the invention.

FIGURE 6 is a transverse sectional view on the line 6—6 of FIGURE 5.

FIGURE 7 is a perspective view of the form of anchoring device used in FIGURES 5 and 6.

FIGURE 8 is a view similar to FIGURE 5 showing the device in a partially assembled condition.

In the embodiment of the invention illustrated in FIGURES 1, 2, 3 and 4 there is shown a fragmentary section of a door 10. A transverse substantially cylindrical bore

11 extends from one face 12 of the door 10 to another face 13. A hole forming a second and smaller bore 14 extends inwardly from an edge 15 into and communicating with the bore 11. With respect to the bores just described, they are formed in a conventional manner and have the same relationship as has been in use for a considerable period of time for the mounting of door locks of the cylinder lock type with which this disclosure is concerned.

A latch bolt assembly included a casing 16 is here shown as being substantially cylindrical in cross-section and has an annular plate or flange 17 located at its outer end in a position such that it bears against the bottom of a depression 18 in the edge 15 of the door.

In the latch bolt casing is a reciprocating latch bolt 19, the mechanism of which is substantially conventional.

30 In the form chosen for the purpose of illustration there is shown as part of the latch bolt assembly an extension comprising parallel plates 20 and 21 which may be secured together by some appropriate device such as a rivet 22 in order to contain a hub 23 to which may be attached 35 a conventional roll-back cam 24.

The parts identified are those which comprise any one of a number of substantially conventional cylinder latch bolt mechanisms. In the interest of clarity, the operating mechanisms featuring knob and spindle have been 40 omitted.

In order to anchor the latch bolt casing in the position illustrated in FIGURES 1, 2, and 3, a loop such as that illustrated in FIGURE 4 and identified by the reference character 25 maybe employed. The loop shown by 45 way of illustration is of relatively stiff resilient wire and is provided with bent ends 26 and 27 and includes an arcuate portion 28. In the plate 20 are provided apertures 29 and 30 into which the bent ends 26 and 27 are inserted. When

50 the loop is assembled with the latch bolt casing the ends 26 and 27 are first inserted into the respective apertures and the loop is then sprung sufficient to permit the arcuate portion 28 to be pressed into the position shown in FIGURES 1, 2, and 3. As there illustrated, the arcuate portion is received within the innermost end of the smaller bore 14, thereby locking it in place and bears against the junction of the inner end of the small bore 14 with the larger bore 11.

When this form of the device is assembled, the latch bolt casing is first inserted in position, as shown in FIGURES 1 and 2. It should preferably be pressed as far in as it can be and until the plate or flange 17 is within the depression 18 and bears against the appropriate edge portion 15 of the door. The loop 25 is then applied as has just been described and when once in position the resiliency

resident in the loop will tend to force the extension embodied in the plates 20 and 21 inwardly or in a direction from left to right, as viewed in FIGURES 1 and 2. This will tend to press the plate or flange 17 against the edge of the door and will firmly anchor the latch bolt casing in proper operative position wherein the requisite operating mechanism can be attached in a substantially conventional fashion.

In a form of the invention illustrated in FIGURES 5, 6, 7, and 8 the same latch bolt casing is mounted in the hole or bore 14 with plates 20 and 21 extending into the mid-portion of the bore 11.

In order to anchor the casing 16 and attendant parts in the position shown there is provided in this instance a wire spring 32 which is shown in perspective view in FIGURE 7. The spring preferably consists of a single length of wire wherein the wire is turned to form a loop 33 at the mid-portion surrounding a hole 34. The diameter of the hole 34 is slightly larger than the outside diameter of a rivet end 31 so that the loop 33 can be slipped comfortably over the end of the rivet whereupon the rivet is peened over at its ends to fasten the loop in place. Another fastening method is to force loop 33 to expand over the larger head of the rivet and then to be retained by said rivet head.

Arms 35 and 36 attached to the loop extend outwardly in the general form of a V. The arm 35 terminates in a bent end 37 providing a rounded corner 38 whereas the arm 36 terminates in a bent end 39 providing a rounded corner 40. Initially the arms 35 and 36 spread into the form of a V substantially wider than the spring will have when placed in anchoring position, it being understood that the arms can be pressed toward each other in a spring-like fashion wherein the resistance is provided not only by the tension in the arms but also the tension in the loop 33.

When the casing including the latch bolt assembly with the spring 32 attached is to be anchored by use of the spring 32, the spring arms are pressed together and the casing is inserted into the small bore 14 in the same manner as previously described so that the plate or flange 17 is received in the depression 18 and the plates 20 and 21 extend into the bore 11 placing the hub in a substantially central position. The spring 32 slides freely through the small bore as shown in FIGURE 8 until it is entirely within the large bore 11.

Once in position the arms 35 and 36 spring outwardly away from each other and the rounded corners 38 and 40 are forced outwardly into engagement with the wall of the bore 11. As described the spring anchors with sufficient firmness to hold the casing in its proper position until a spindle (not shown) of a conventional door lock can be passed into and through the hub 23, after which the latch bolt casing cannot be removed in the absence of removal of the spindle. On those occasions where it may be desired to remove the casing, removal can be accomplished by the simple expedient of collapsing the arms 35 and 36 against each other by manual pressure after the spindle has been removed, and the spring ends started outwardly through the small bore 14, permitting extraction of the casing 16 and its attendant parts.

From the foregoing description of two types of spring member for removably anchoring a latch bolt assembly and casing in a door it can be understood that the physical embodiments of devices shown exhibit a method of attachment or anchoring by a spring-like agency, the important aspect of which consists of making use of walls of the bore normally made to receive the parts and pressing against oppositely positioned areas of the door in order to force and retain the latch bolt in position by such agency.

The method herein made reference to where in certain specific types of anchoring elements have been described is however one capable of use with different of hardware, with springs of different descriptions and in configurations and variations which may depart materially from the spe-

cific structures but which nevertheless continue to employ the method of pressing resiliently and simultaneously in opposite directions, one pressure being against the latch bolt casing and the other pressure being against some interior portion of the door and to perform the method in company with these expedients.

It will be understood from the foregoing description in company with the disclosure in the drawings that there has been provided a method for anchoring a latch bolt casing which assumes substantially conventional forms and proportions such as may normally be employed and which needs no special design or construction other than the simple expedient shown in order by use of a simple anchoring element to be firmly anchored in place upon the material of the door itself.

While I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent devices.

Having described my invention, what I claim as new in support of Letters Patent is:

- 25 1. A method of installing a latch bolt assembly in a door, comprising forming a configuration at the inside end of said latch bolt assembly, boring a transverse hole through the door from face to face thereof, boring a second hole smaller in diameter than the transverse hole from a vertical edge of the door to a location meeting the first hole, forming a piece of resilient material into a self-expanding anchoring means having opposite ends, forming a configuration at one of said ends to fit the configuration of said latch bolt assembly, forming at the other end of said anchoring means a configuration adapted to engage portions of the door within the larger one of said holes, expanding said anchoring means transversely to a breadth initially greater than the distance between laterally opposite portions of said other end of the anchoring means at the location of engagement with said portions of the door, applying the configuration at said one end of the anchoring means to the configuration of the latch bolt assembly, inserting the latch bolt assembly into the second hole from the edge of the door inwardly until a substantial portion of the latch bolt assembly is located within said transverse hole, pressing a casing portion of said assembly against the door adjacent the edge, thereby to limit inward positioning of the assembly, and pressing said anchoring means into engagement with the door at said portion of said door within said transverse hole and anchoring the assembly in position by continuing expansion pressure of said anchoring means at three or more points of contact between the latch bolt assembly and the door at said portion of the door within said transverse hole, whereby to both center and retain said latch bolt assembly in position.
- 30 2. A method of installing a latch bolt assembly in a door, comprising forming a configuration on said latch bolt assembly, forming a piece of resilient material into a self-expandable anchoring element having opposite ends, forming a configuration at one of said ends to fit the configuration of said latch bolt assembly, forming at the other end of said anchoring element a configuration adapted to engage portions of the door by spreading said other end wider than said one end in preparation for multiple point contact with the door material in the area of said transverse hole, boring a transverse hole through the door from face to face thereof, boring a second hole smaller in diameter than the transverse hole from a vertical edge of the door to a location meeting the first hole, expanding said anchoring means transversely to a breadth initially greater than the diameter of said second hole, applying the configuration of the anchoring element to the configuration of said latch bolt assembly, compressing the anchoring element and inserting a casing

- 60 3. A method of installing a latch bolt assembly in a door, comprising forming a configuration on said latch bolt assembly, forming a piece of resilient material into a self-expandable anchoring element having opposite ends, forming a configuration at one of said ends to fit the configuration of said latch bolt assembly, forming at the other end of said anchoring element a configuration adapted to engage portions of the door by spreading said other end wider than said one end in preparation for multiple point contact with the door material in the area of said transverse hole, boring a transverse hole through the door from face to face thereof, boring a second hole smaller in diameter than the transverse hole from a vertical edge of the door to a location meeting the first hole, expanding said anchoring means transversely to a breadth initially greater than the diameter of said second hole, applying the configuration of the anchoring element to the configuration of said latch bolt assembly, compressing the anchoring element and inserting a casing
